UNITED STATES PATENT OFFICE

2,685,276

VALVE OPERATED PRESSURE CONTROL

Charles P. Dyken, Saukville, Wis.

Application April 5, 1951, Serial No. 219,494

1 Claim. (Cl. 121—45)

1

My invention relates to improvements in pressure control and more particularly to a control for hydraulic or pneumatic pressure.

The object of my invention is to provide a means for positively controlling pressure.

Another object of my invention is to provide a means for providing a gradual pressure, a full pressure, or an immediate release of the pressure applied to an actuating means and this is accomplished by manual manipulation or by mechanical control.

It is manifest to any one familiar with the art that in the manipulation of various types of machines, apparatuses or actuating mechanisms it is oftentimes desirable to apply full pressure quick, or to apply a gradual pressure, and this is usually accomplished by valve manipulation or action. With the arrangement shown it is possible to obtain a quick feed, a gradual feed, or a rapid release with but a single operating lever.

Other and further objects of my invention will become more apparent as the description proceeds when taken in conjunction with the drawing, in which

Figure 1 is a side, fragmentary, cross sectional view of the assembled device.

Figure 2 is a cross sectional view of the assembled units with the valve arrangement set for quick feed of the pressure.

Figure 3 is a similar view of the assembled units with the valve arrangement set for a gradual feed of the pressure, and

Figure 4 is a similar view as shown in Figures 2 and 3, with the valve arrangement set for a quick release or exhaust.

Similar characters of reference indicate corresponding parts throughout the several views and referring now to the same, the character 10 indicates the inlet to the assembled unit, for supplying pressure either hydraulically or pneumatically by means of a pump or a compressor to a tubular member 11 which enters a valve 12 at 13. The valve 12 is operated either mechanically or manually by the lever 14 which rotates an inner member 15 provided with a port 16 having an inlet 17 and an outlet 18.

There is an outlet tube 19 leading from the valve 12 and an exhaust tube 20 also leading from the valve 12 to a reservoir (not shown), in the event that the device is used for hydraulic pressure control, or to the outside atmosphere when the device is employed for pneumatic pressure control.

A by-pass tube 21 leads from the tubular member 11 to a control valve 22 which may be of any

2

conventional design and is shown in the illustration as regulated manually by the screw 23, operated by the hand wheel 24, for adjusting the opening between the ground seat and the cone point of the screw as shown at 25.

The control valve 22 has a tubular outlet 26 leading to a two-way valve 27 which is provided with a revolving member 28 and is actuated by means of a lever 29 attached by a link 30, to the lever 14 on the main valve 12. The revolving member 28 in the valve 27 is provided with a port 31 and a tubular member 32 extends from the valve 27 to a cylinder 33 which encases a piston 34, and this piston is provided with a rod shown as 35 which is employed to actuate the mechanism being operated. The member 19 enters the tubular member 32 at 36.

The entire unit is a self-contained, closed assembly of tubes and valves to supply the liquid or air to a cylinder shown as 33. The manipulation of the handle 14 on the valve 12 revolves the member 15 in the valve 12 so as to place the port 16 in position as shown in Fig. 1, when a quick or rapid travel of the piston 34 within the cylinder 33 is desired. In this manner the valve 27 is closed as shown in Fig. 1, the pressure of the air or liquid entering the assembly 10 will flow directly through the valve 12 into the cylinder 33 causing the piston 34 to move upward.

When a control of the pressure is desired the lever or handle 14 in the valve 12 is moved so that it will close the valve 12 as shown in Fig. 2, and open the valve 27, thereby causing the liquid or air entering at 10 to flow through the tube 21 to the control valve 22 which is set at a pre-determined point, and through this valve 22 through the tube 26 to the valve 27 and into the cylinder 33. This will cause the piston 34 to rise upward at a speed determined by the setting of the control valve 22.

In Fig. 4, I show an arrangement in which the lever 14 is set to open the port 16 to the tubular member 19 and the exhaust outlet 20, and inasmuch as the valve 27 is in a closed position, the piston 34 will force the air or liquid out of the cylinder 33 through the tubes 32 and 19, where it will be exhausted out of the valve 12 at 20.

The drawings illustrate the arrangement employed when a weight (not shown) is lifted by the piston 34, and when the pressure of the liquid or air in the cylinder 33 is released the piston 34 will force the air or liquid out of the cylinder due to the weight of the piston, which is equivalent to the piston and cylinder arrangement employed for raising the top roller in my rug rolling ma-

chine covered by my Patent No. 2,573,188, dated October 13, 1951.

While I have shown a particular arrangement of the component parts constituting my device, I am fully cognizant of the fact that many changes may be made in the direction, size and arrangement of the tubular members without affecting their operativeness, and I reserve the right to make such changes that do not affect the spirit of my invention or the scope of the 10 appendant claim.

Having thus described my invention what I claim and desire to secure by Letters Patent in the United States is:

A pressure control comprising a tubular supply member leading to an individual three-way valve having an inlet port, an outlet port, and an exhaust port, a separate manually controlled pressure regulating valve, both of said valves equipped with operating levers, said pressure regulating valve having its inlet connected by tubular means to said supply member, a separate two-way valve having an inlet port and an outlet port, an operating lever connected to said two-way valve, tubular means connecting the outlet of said pressure regulating valve to the inlet of said two-way valve, a cylinder, a piston within said cylinder, a tubular member connected to said cylinder

5 and leading to both the outlet ports of said two-way and three-way valves, and a link member attached to the operating lever of said three-way valve at one end and to the operating lever of the two-way valve at the other end, so as to open said two-way valve when said three-way valve is closed and closing said two-way valve when said three-way valve is open.
